TOILET SEAT

Filed Dec. 23, 1929

Fred Brousseau,
INVENTOR.

BY J. Stanley Birch

ATTORNEY.

UNITED STATES PATENT OFFICE

FRED BROUSSEAU, OF WYANDOTTE, MICHIGAN

TOILET SEAT

Application filed December 23, 1929. Serial No. 416,021.

This invention relates to improvements in detachable nursery or toilet seats particularly adapted for the use of children.

An object of this invention is to provide a 5 toilet seat for small children constructed in a simple and inexpensive form from a minimum of parts, and adapted to be readily used in connection with the ordinary closet seat.

Another object of this invention is to provide 10 a detachable toilet seat for children formed in such a manner that it may be easily and quickly placed in position on the ordinary closet seat and held in the desired place by means of downwardly extending 15 portions of the toilet seat fitting over the edges of the closet seat. The back-rest being pivotally mounted in bearings integrally formed from the main body portion of the detachable toilet seat.

20 Other objects of this invention will appear from the following detailed description of the device and as disclosed in the single sheet of drawings herewith made a part of this application.

25 In the drawings,

Fig. 1, illustrates an elevational view of the 30 detachable toilet seat in adjusted relationship to an ordinary closet seat, and showing portions in section.

Fig. 2, represents a plan view of the 35 detachable toilet seat.

Fig. 3, illustrates a front elevational view of the 40 detachable toilet seat showing the pivotally mounted back-rest in raised position.

As one form or modification of this invention it is preferred that numeral 1 designate 45 the main body portion of the detachable toilet seat for children, made from any suitable material such as sheet metal. The main body portion 1 being formed from a single piece of material, and shaped in such a manner that it will readily fit into position over the ordinary closet seat 2, usually pivotally mounted to a bowl 3, as clearly shown in Fig. 1.

The main body portion 1 is formed having 50 an opening 4 for registering with the opening 18 in the closet seat 2, while downwardly extending flanges 5 and 6 are provided for firmly holding the seat 1 in fixed relationship to the closet seat 2, no lateral

movement being possible by this arrangement. At the same time the flange 6 functions to provide a comfortable seat for the child, all danger of contacting with the free edge of the opening 4 being eliminated. The 55 members 7 and 8 of the main body portion 1 extend rearwardly over the seat 2, and are provided at their ends with downwardly extending flanges 9 and 10 for fitting over the rear of the seat 2, and forming additional 60 means for maintaining the detachable seat 1 in proper relationship to the close seat 2.

A back-rest 17 is provided, made from any suitable material, such as sheet metal obtained from the cutout portion between the 65 members 7 and 8 of the main body portion 1. The section 17 is preferably connected to a frame 14 as shown in Fig. 3, by bending the free edges around suitable portions of the rod frame 14, which is formed having outwardly 70 extending elements 15 and 16 adapted to be pivotally mounted in upwardly extending bearings 12 and 13 integrally formed from the main body portion 1. An upwardly and rearwardly extending stop element 11 is 75 formed from the main body portion 1, the ends of which, as at 19 and 20, are securely fastened by solder or otherwise to the bearings 12 and 13, thereby providing a simple 80 and strong supporting device for the pivotally mounted back-rest 17, as disclosed clearly in Fig. 1.

This invention provides a detachable seat for children which may be readily adjusted to any ordinary closet seat, the downwardly 85 extending flanges 5, 6, 12 and 13 function to hold the seat from lateral movement, and the complete device is formed from practically a single piece of material, the back rest frame being pivotally mounted in the main body 90 portion, thereby providing a seat inexpensive of manufacture and efficient in use.

What I claim is—

1. An auxiliary seat for a toilet seat comprising a single piece of material having 95 downwardly extending flanges for fitting over the edges of the toilet seat, upwardly extending flanges integrally formed from the single piece of material, a back-rest pivotally mounted in the upwardly extending flanges. 100

2. An auxiliary seat for a toilet seat comprising a single piece of material having downwardly extending flanges for fitting over the edges of the toilet seat, upwardly extending flanges integrally formed from the single piece of material, a back rest pivotally mounted in the upwardly extending flanges, a stop for the back rest extending upwardly and rearwardly and formed from the single piece of material.
3. An auxiliary seat for a toilet seat comprising a body portion formed from a single piece of material and having an opening for registering with the opening in the toilet seat, said body portion having downwardly extending flanges for fitting over the edges of the toilet seat and provided with integral rearwardly extending spaced members having at their rear ends downwardly extending flanges for fitting over the rear edge of the toilet seat, a back rest pivotally mounted on the body portion adjacent and between the forward ends of said rearwardly extending spaced members, and a stop for the back rest extending upwardly and rearwardly and formed from the single piece of material between said rearwardly extending spaced members.

In testimony whereof I affix my signature.
30 FRED BROUSSEAU.
